UNITED STATES PATENT OFFICE.

WILLIAM A. SPARKS, OF CHARLESTON, WEST VIRGINIA, ASSIGNOR TO SPARKS DRILLING JAR COMPANY, OF CHARLESTON, WEST VIRGINIA, A CORPORATION OF WEST VIRGINIA.

METHOD OF MAKING WELL DRILL-JARS.

1,209,346.

Specification of Letters Patent. Patented Dec. 19, 1916.

Application filed October 3, 1913. Serial No. 793,202.

To all whom it may concern:

Be it known that I, WILLIAM A. SPARKS, a citizen of the United States, residing at Charleston, in the county of Kanawha and 5 State of West Virginia, have invented certain new and useful Improvements in Methods of Making Well Drill-Jars; and I do hereby declare the following to be a full, 10 clear, and exact description of the invention, such as will enable others skilled in the art to which it appertains to make and use the same.

In oil well drilling it has been found necessary in practice to make the drilling 15 jars a part of the "string" of tools, and as the tools are very heavy owing to the severe work in drilling through strata of rock, the drill jars are subjected to a great strain, and it is necessary that the jars be constructed 20 of the best material for the purpose. It is well known among those skilled in the art, that the jars are the weakest part of the drilling outfit, and this is especially so when considering the strain imposed 25 upon them in drilling oil wells. In the practical operation of the drilling tools, the jars should be so constructed as to permit the untwisting of the drill rope in the event of the drill tool binding in the rock, otherwise 30 the jars might become broken from the combination of a twisting or lateral strain and the vertical or pulling strain thereon, due to the tendency of the rope to straighten out or untwist under the strain imposed 35 thereon. It is found desirable therefore that the jars should be capable of rotative movement, as well as reciprocating movement, and also that the jars shall withstand the strain imposed thereon, and in the event 40 of breakage of the parts of the jar or other parts of the tool string, that the "fishing" of the broken parts from the well shall be a comparatively easy task.

The rotary motion of drill jars is extremely 45 desirable in preventing the fracture of the jars of the old type and also in protecting the men who are operating the drill. When it becomes necessary, as is frequently the case, to change the string of tools in a well, the jars are raised to the top of the well, and the socket joint on the top of the jars loosened up, usually with the aid of wrenches, "breaking the joint" so that the socket can be unscrewed by hand. The 55 string of tools are then removed from the

hole and raised up into the derrick whereupon the attendant completes the unscrewing of the socket. To do this, involves a back twist upon the rope which is gotten by a wrench attached to the square top of the 60 rope socket. Before the operation is completed the strain on the rope and the wrench becomes severe and accidents are not infrequent due to the attendant losing his grip on the wrench and being knocked from his 65 position by the whirling around of the wrench. Similarly, when attaching the socket to the top of link jars, it is frequently necessary to first back twist the rope in order that in screwing the sockets on the jars 70 there may not be a twisting of the rope as well as the resistance of the screw joint to contend against. The jars of this invention, however, permit of rotary as well as reciprocating movement of the parts with 75 reference to each other thereby obviating the necessity of giving any rotary movement to the socket or twist to the rope either in fastening on or fastening the socket, but the necessary rotary movement can be given by 80 turning the top member of the jar with a wrench engaging the squared portion thereof.

This invention is a method of making well 85 drill jars, having for its object to produce a set of jars which may be permanently united; which will retain the initial strength of the metal from which they are made; which will be free from screw threaded 90 parts, and the material of the jars not weakened by subjecting the parts thereof to welding operations.

Well jars constructed in accordance with this invention will possess greater strength than the ordinary link jars, are not liable 95 to become choked with fragments of rock or other debris and rendered partially or wholly inoperative, as is frequently the case with the link jars, will give a greater impact due to their form of construction, are not 100 liable to become broken within a well when subjected to the usual operating strain, will outlast several sets of jars of the link type, or those jars constructed with screw threaded parts, or those subjected to welding operations. Many attempts have been made to produce a jar having the desirable reciprocating and rotative movement, and which are durable in their construction.

The method herein set forth produces a jar the parts of which are permanently interlocked, and which are comparatively free from battering, thereby obviating the sticking or binding of the parts. The freedom from welding heating operation insures the life of the material and adds greatly to the efficiency of the jars, especially during drilling through rock by the tool.

10 The drill jars of this invention are produced from solid pieces of metal, such as high grade steel, one member of each set of jars being formed with an integral shank and head, forming a piston, while the other member is provided with a chamber which permits of the reciprocating and rotary movements of the head or piston therein. The chamber is bored to produce a seat intermediate the end thereof, and also a seat 20 for the head at one end. The chamber member is then subjected to heat, and the piston or head inserted in said chamber, and the open end of the chamber member is compressed around the shank, permanently locking the two members together, and at the same time forming a seat at each end of the chamber for the piston or head.

The method is partially illustrated in the accompanying drawing, in which,

30 Figure 1, is a side elevation of a bar of metal from which the jar members are formed. Fig. 2, illustrates the upper or piston jar member after it has been turned and otherwise constructed from the bar of 35 metal. Fig. 3, illustrates the first step in constructing the socket member. Fig. 4, shows the chamber produced in the socket member. Fig. 5, shows the lower seat for the head added to Fig. 4. Fig. 6, shows the addition of the drain duct to the chamber. Fig. 7, is an enlarged detail view showing the cut for the upper seat. Fig. 8, shows one position of the piston member within the chamber when ready to unite the parts. 40 Fig. 9, shows the upper end of the socket member compressed around the shank of the piston member. Fig. 10, is an enlarged view showing the piston head provided with longitudinal grooves to permit of the passage 50 of debris through the socket.

The invention embodies the construction of well drill jars by which the parts thereof may be permanently interlocked, and which will afford a maximum jar with a minimum 55 of wear upon the parts thereof, and especially the construction of the jars of the type described out of high carbon steel or other extra durable and refractory metal so to preserve unimpaired the original 60 strength, hardness and resistance to the wear of the metal, which qualities are necessarily impaired by either casting or welding.

The material from which the jar members are constructed is preferably high grade 65 steel, although it is obvious that they may

be constructed of other suitable metal or alloys of metal.

A bar of metal of the proper grade and thickness, such as illustrated in Fig. 1, is placed in a lathe, or other suitable tool, 70 turned to produce the upper member 1 having the shoulder 2, a shank 3, and a head or piston 4, all integral with the member. The free end of the head is now preferably rounded as shown at 5, while the portion of 75 the head 4 which joins the shank 3 is formed with an abutting surface 6, which may be of any suitable or preferred form, but preferably rounded. The head 4 may be provided, also, with refuse grooves 9, if 80 desired. The member is provided also with the usual cutaway portion 7 and the upper collar 8, together with suitable means, as in 9, for uniting the member to the socket to which is attached the rope suspending the 85 string of tools.

Figs. 3 to 8 illustrate the construction of the socket member. In Fig. 3 a bar of metal such as illustrated in Fig. 1 is placed in a suitable tool, such as a lathe, and the portion 90 of the bar reduced in diameter as illustrated at 10 in Fig. 3, or this process of reduction may be accomplished in whole or in part by forging under the hammer. The usual coupling end 11 is also provided, as 95 well as the reduced squared portion 12. In Fig. 4, there is illustrated a section through the chamber member, wherein the bar of metal is bored, as at 13, to produce the chamber 14 therein. In Fig. 5 the lower end of the 100 chamber is rounded as at 15, to receive the rounded end 5, of the head 4, and to substantially fit the head. In Fig. 6, the metal is suitably bored to produce a duct, 16, for the exit of the material which may accumulate 105 in the chamber during the operation of the jar in a well. It will be understood that this chamber 14 is bored with straight walls in Figs. 4, 5 and 6, leaving a greater thickness of metal at 17 than at 18 to form the 110 walls of the chamber. After the chamber 14 is bored as aforesaid an annular cut is made around the inside of the same to produce the shoulder 20 to form an upper seat for the head or piston. This may be produced by any suitable means, such as a counter bore, by cutting back and feeding the tool by a taper attachment. This shoulder 20 corresponds to, and is adapted to 115 form a seat for, the shoulder 6 of the head or piston when the two members are brought together. This shoulder 20 should form a perfect seat for the upper end of the head to produce the best results and prevent distortion of a part of the head during operation. Having bored the lower member as indicated, it is heated to permit of its being 120 readily molded or compressed. An ordinary red heat is found amply sufficient. The head 4 of the piston member is now inserted into 125

130

the chamber 14 and moved to a position below the shoulder seat, 20, whereupon the chamber member is placed in a suitable tool, such as a hammer die or press, and the upper 5 end thereof, having the thickened walls 17, compressed toward the shank 3 of the piston member, to a position substantially as shown in Fig. 9. The outer surface of the chamber member is now substantially of the same circumference throughout its length. The parts 10 are thence permitted to cool. Should the socket member be increased in length during the compressing operation, the jar members are placed in a lathe, or other suitable tool, 15 and the end 21 of the socket member cut away until the shoulder 2 will engage the end 21 of the socket member simultaneously with the engagement of the end 5 of the head 4 with its seat 15. This construction permits 20 of the double impact of the parts of the jar at two points, thereby giving a greater jar, or increased efficiency, with less strain or battering of the parts.

Having thus described my invention, what 25 I claim as new, and desire to secure by Letters Patent, is:

1. The method of producing well drill jars comprising the formation of a piston member having an elongated shank and a head, 30 forming a socket member with an elongated chamber, inserting the head of the piston member into the socket chamber, and compressing the wall of an end of the socket member around the elongated shank to connect the piston and socket members and permit of reciprocating and rotating movements of the head within said chamber.

2. The method of producing a well drill jar from two pieces of metal comprising the 40 formation of a piston member having an elongated shank and a head, forming a socket member with a chamber of greater length than said head, forming a seat for the head at one end of the chamber, cutting a 45 groove in the wall of the socket member near the other end of the chamber, and compressing the wall of an end of the socket member around the shank of the piston member to connect the piston and socket members and 50 to form a seat for the head at said groove.

3. The method of producing a well drill jar from two pieces of metal comprising the formation of a piston member having an elongated shank and a substantially cylindrical head, forming a socket member having a portion thicker near one end, forming a cylindrical chamber in the thicker end of the socket member of greater length than said head to have the wall of said chamber of 60 varying thicknesses, cutting a groove in the wall of the chamber at a thickened portion

to reduce such portion at the groove to substantially the thickness of a thinner part of the wall of the chamber, compressing the thicker portion of the wall of the socket 65 member around the shank of the piston member to connect the piston and socket members and to form a seat for the head at one end of the chamber by distorting the formation of the grooved portion of the chamber 70 wall.

4. The method of producing a well drill jar from two pieces of metal comprising the formation of a piston member having an elongated shank and a substantially cylindrical head thereon, rounding the free end 75 of the head, forming a socket member within an open ended chamber therein of greater length than said head, and with a wall of varying thickness, forming a rounded seat 80 at one end of said chamber for the rounded end of the head, inserting the piston head into the chamber of the socket at a point intermediate the ends of the chamber, and compressing the chamber end of the socket 85 member having the thickened wall, upon the shank of the piston member to house the head within the chamber and serve as a stop to the movement of the piston head in one direction.

5. The method of producing a well drill jar from two pieces of metal comprising the formation of a piston member having a shoulder, an elongated shank and a substantially cylindrical head thereon, rounding the 95 free end of the head, forming a socket member with an open ended chamber therein of greater length than said head and with a wall of varying thickness, forming a rounded seat at one end of said chamber for the 100 rounded end of the head, forming another seat intermediate the ends of said chamber and into a thickened part of the wall of the socket member, inserting the piston-head into the chamber of the socket member and 105 at a point between said seats, compressing the chamber end of the socket member having the thickened wall upon the shank of the piston member to house the head within the chamber, and thereafter cutting away a portion of the chamber end of the socket member 110 until the shoulder of the piston member engages the chamber end of the socket member simultaneously with the engagement of the rounded end of the piston-head 115 with the rounded seat of the socket member.

In testimony whereof, I affix my signature, in presence of two witnesses.

WILLIAM A. SPARKS.
